His Attorney.

UNITED STATES PATENT OFFICE

WILLIAM K. KEARSLEY, OF SCHENECTADY, NEW YORK, ASSIGNOR TO GENERAL ELECTRIC COMPANY, A CORPORATION OF NEW YORK

DIAPHRAGM FOR LOUD SPEAKERS

Application filed October 1, 1926. Serial No. 138,982.

The present invention relates to sound reproducing devices of the type commonly known as loud speakers, and more particularly to a form of diaphragm, suitable for 5 loud speakers, which may be economically constructed and which is adapted to faithfully reproduce sounds of both high and low frequency.

The novel features which I believe to be 10 characteristic of my invention are set forth with particularity in the appended claims. My invention itself, however, will best be understood from reference to the following specification, taken in connection with the 15 accompanying drawings, in which Fig. 1 represents a view, partly in elevation and partly in section, of an assembled diaphragm and motor therefor; Fig. 2 is a perspective view of one section of the dia- 20 phragm and the central supporting cylinder therefor; while Fig. 3 is a front elevation of the sound reproducing device.

On my drawings I have indicated at 1 a magnet system comprising an annular pole 25 piece 2 and a central core 3 provided with a winding 4. A screw threaded member 5 engages the end of the core 3 and has mounted thereon a pair of sleeves 6 and 7, which co-operate with member 5 to secure in position 30 two angular metal brackets 8 and 9. A stiff hollow paper cylinder 10 is mounted to vibrate in the air gap between core 3 and polepiece 2. The paper cylinder is maintained in position by means of threads 11 35 and 12 which extend through the metal brackets 8 and 9 and the cylinder 10, as clearly indicated in Fig. 2. The threads prevent lateral movement of the cylinder but permit movement thereof in an axial direction. An actuating coil 13 is mounted on 40 one end of cylinder 10 and is movable in the air gap between the core 3 and polepiece 2. A series of tubular members 14, constructed of paper, are radially mounted adjacent one 45 another at the opposite end of cylinder 10 and are compressed or flattened at their opposite ends to provide a rigid surface with radially extending corrugations where the adjacent sides of the tubular members meet. 50 The tubes 14 may be secured to cylinder 10

in any suitable manner, as by an adhesive. Since the surfaces of the flattened end portions of members 14 are substantially 90° displaced from one another, a substantially flat diaphragm of great rigidity is provided 55 and at the same time the surface of the diaphragm is substantially continuous with no gaps between adjacent tubes. An adhesive may be applied at the line of contact of adjacent surfaces of members 14 to give fur- 60 ther rigidity if desired. The diaphragm as thus constructed is movable as a whole in an opening 15 of the container for the loud speaker unit. No support is required at the outer edge of the diaphragm, and while the 65 diaphragm is extremely light in weight, it has, nevertheless, owing to the form of the tubular members, sufficient rigidity to maintain its shape indefinitely.

What I claim as new and desire to secure 70 by Letters Patent of the United States is:

1. A diaphragm comprising a hollow cylindrical member and a series of hollow tubular members radially mounted thereon forming thereby a substantially continuous 75 surface.

2. A diaphragm adapted to be vibrated, said diaphragm comprising a series of hollow members radially arranged about a central axis and flattened at opposite ends, 80 thereof to thereby provide a substantially continuous surface.

3. In a sound reproducing device, a diaphragm comprising a series of tubular members flattened at opposite ends thereof and 85 mounted adjacent one another to thereby provide a substantially continuous surface.

4. A diaphragm comprising a hollow cylindrical member, a series of hollow tubular members mounted thereon and ex- 90 tending in radial directions from the cylindrical member, each of said tubular members having flattened end portions displaced substantially 90° to thereby provide a substantially continuous surface. 95

5. A diaphragm comprising a hollow cylindrical member, a series of hollow tubular members mounted thereon and extending in radial directions from the cylindrical member, a stationary member, and a plural- 100

ity of cords to support said cylindrical member from said stationary member, said cords having portions extending between said members to prevent lateral movement of
5 said cylindrical member and to permit axial movement thereof.

In witness whereof, I have hereunto set
my hand this 30th day of September, 1926.

WILLIAM K. KEARSLEY.
